WRITING INSTRUMENT

Joseph P. Mayer, Round Lake, Ill.

Application June 24, 1955, Serial No. 36,673

Term of patent 14 years

(Cl. D74—17)

Figure 1 is a side elevational view of the writing instrument of this invention with the pen portion in extended writing position;

Figure 6 is a side elevational view of the writing instrument of this invention similar to Figure 1 but on a reduced scale and with the pen portion in withdrawn storage position;

I claim:

The ornamental design for a writing instrument, as shown.
